US0D1090495S

(12) **United States Design Patent** (10) **Patent No.:** **US D1,090,495 S**
(45) **Date of Patent:** **** Aug. 26, 2025**

(54) **REMOTE CONTROL**

(71) Applicant: **Amazon Technologies, Inc.**, Seattle, WA (US)

D752,555 S 3/2016 Langhammer et al.
D763,830 S 8/2016 Jones
D795,842 S 8/2017 Cha et al.
(Continued)

(72) Inventor: **Jonathan Howard Biddle**, San Francisco, CA (US)

FOREIGN PATENT DOCUMENTS

(73) Assignee: **Amazon Technologies, Inc.**, Seattle, WA (US)

EM 015006719001 12/2022
EM 015007839-0002 1/2023
(Continued)

(**) Term: **15 Years**

(21) Appl. No.: **29/964,412**

(22) Filed: **Sep. 23, 2024**

D728,529 S	5/2015	Seflic et al.

FIG. 1 is a top, front, right-side perspective view of a remote control;

FIG. 2 is a bottom, back, left-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The dashed broken lines depict portions of the remote control that form no part of the claimed design.

1 Claim, 8 Drawing Sheets
